(57) **CLAIM**

The ornamental design for a sealant bottle for tire repair kit, as shown and described.

DESCRIPTION

FIG. 1 is a front, left perspective view of a sealant bottle for tire repair kit showing my new design;

FIG. 2 is a rear, right perspective view thereof;

FIG. 3 is a front view thereof;

FIG. 4 is a rear view thereof;

FIG. 5 is a left side view thereof;

FIG. 6 is a bottom view thererof; and,

FIG. 7 is a top view thereof.

The right side view is a mirror image of the left side view.

The portions in broken lines are directed to the environment and form no part of the claimed design.
